UNITED STATES PATENT OFFICE

ROBERT E. ANDERSON, OF MORRISVILLE, PENNSYLVANIA, ASSIGNOR TO ROBERTSON ART TILE COMPANY, OF MORRISVILLE, PENNSYLVANIA, A CORPORATION OF NEW JERSEY

SAGGER

Application filed December 11, 1929. Serial No. 413,213.

My invention relates to an improvement in saggers, more particularly for use in firing tile.

Heretofore it has been customary to utilize, in the firing of for example tile, saggers of box-like form. The saggers, as heretofore used, have been made of refractory material and have comprised a base and four sides to contain tile to be fired. The saggers heretofore used have been open to many objections, principally in that they comprise a substantial bulk of material in proportion to the amount of tile contained and which is required to be heated in addition to the tile, 15 they are relatively heavy and cumbersome to handle and require a substantial amount of room for storage, they are easily damaged or broken, they negative uniform heating of the tile and during the firing the major portion of the tile contained in the sagger cannot be inspected.

In accordance with my invention, I provide a sagger which is very largely lighter than the saggers heretofore known and which 25 is collapsible, thus reducing the heat required to fire the tile and enabling easy handling and storage in relatively restricted space. The sagger in accordance with my invention is so constructed as to enable the tile to be inspected at any time and to insure rapid and uniform heating and cooling. Further, the sagger in accordance with my invention is so constructed as to enable the replacement of damaged parts.

The construction of the sagger in accordance with my invention will be understood from the following description, with reference to the accompanying drawings, in which:

40 Fig. 1 is a perspective view of a sagger embodying my invention.

Fig. 2 is a perspective view of the several parts of the sagger separately.

Fig. 3 is a cross sectional view of the sagger shown in Fig. 1, taken between its ends.

Fig. 4 is a perspective view, partly broken away, showing a plurality of saggers superimposed.

With reference to the drawings *a* indicates 50 a base, desirably of rectangular shape and

formed from suitable refractory material. The base is provided adjacent its ends with apertures *b*, *b* and with flanges *c*, *c* which extend adjacent to the sides of the base to points adjacent to its ends. *d*, *d* indicate end members, which are duplicates and which are formed from suitable refractory material. Each of the end members is provided with a tenon *e* extending from one of its ends and with feet *f* positioned adjacent to the tenon and extending at right angles thereto from the end of the member. Each of the end members is provided also with a recess in its end opposite to that from which the tenon extends.

In the assembled sagger the end members extend vertically from the base member, being retained in position through the extension of the tenons on the end members into the apertures in the base and through the engagement of the feet *f* with the base. The tenons *e* are a loose fit in the apertures *b* and are desirably tapered in order to avoid binding of the tenons in the apertures through expansion. Further, the tenons desirably extend into the end members slightly beyond the lower surface of the feet *f*, as indicated at *h*, *h*, Fig. 2.

In using the sagger embodying my invention a layer of sand is placed on the upper surface of the base between the flanges *c*, which serve in conjunction with the end members, against which the ends of the flanges desirably abut, to retain the sand and enable it to be readily leveled off. Between the end members the tile or biscuits to be fired are stacked and the sagger is then placed in the usual furnace.

As will be obvious, the sagger in accordance with my invention lends itself to stacking as shown in Fig. 4, in which a plurality of saggers are illustrated stacked one upon another, it being customary to stack the saggers on, for example, a car for introduction into a furnace. The stacking of saggers embodying my invention in no way negates the free circulation of heat to the contained tiles or biscuits, since the recesses in the end members and the fact that the side members are open provide for adequate circulation to af.

ford uniform heating of the contained tiles or biscuits and likewise for uniform cooling thereof.

It will now be noted that the saggar in accordance with my invention lends itself admirably for the purpose intended and that due to its relative lightness as compared with saggers as heretofore constructed, it has been found that effective firing may be obtained with the use of temperatures as much as 150° F., or more, lower than with the saggers heretofore used. Further, it will be noted, as has been indicated, that the saggar embodying my invention may be easily handled and may be disassembled for storage and, at the same time, due to the construction it will be found of adequate rigidity when assembled. Further, it will be noted that due to the light weight of the saggar embodying my invention, tiles or biscuits to be fired may be rapidly brought up to the desired temperature and rapidly cooled and, at the same time, the tiles or biscuits will be uniformly heated and cooled when the saggers are stacked, due to the open sides and the recessed end members.

What I claim and desire to protect by Letters Patent is:

1. A saggar formed from refractory material and comprising a base provided with apertures adjacent its opposite ends and end members each provided with a tenon at one end and having a recess formed in its opposite end, the end members extending vertically from the base and being retained in position through engagement of the tenons in the apertures.

2. A saggar formed from refractory material and comprising a base provided with apertures adjacent its opposite ends and end members each provided with a tenon at one end and having a foot adjacent said tenon extending at right angles to the tenon, the end members extending vertically from the base and being retained in position through engagement of the tenons in the apertures and through engagement of the feet with the base.

3. A saggar formed from refractory material and comprising a base provided with apertures adjacent its opposite ends and having flanges extending along opposite sides to points adjacent its ends and end members each provided with a tenon at one end, the end members extending vertically from the base and being retained in position through engagement of the tenons in the apertures.

4. A saggar formed from refractory material and comprising a base provided with apertures adjacent its opposite ends and having flanges extending along opposite sides to points adjacent its ends and end members each provided with a tenon at one end and having a foot adjacent said tenon extending at right angles to the tenon, the end members

extending vertically from the base and being retained in position through engagement of the tenons in the apertures.

In testimony of which invention, I have hereunto set my hand, at Morrisville, Pa., on this 9th day of Dec., 1929.

ROBERT E. ANDERSON.
